UNITED STATES PATENT OFFICE.

ALEXANDER GORDON, OF ROCHESTER, NEW YORK.

IMPROVEMENT IN STRAW-CUTTERS.

Specification forming part of Letters Patent No. 56,743, dated July 31, 1866.

To all whom it may concern:

Be it known that I, ALEX. GORDON, of Rochester, in the county of Monroe and State of New York, have invented a new and useful improvement in the manner of supporting the adjustable feed-roller of feed-cutters; and I do hereby declare that the following is a full, clear, and exact description thereof, reference being had to the accompanying drawings, making part of this specification, in which—

Figure 1 is a vertical section of a feed-cutter having my invention attached. Fig. 2 is an inverted plan of the yoke *y* and spring *s*.

Like letters indicate corresponding parts.

This invention relates to that class of feed-cutters having an upward cut, and in which the lower feed-roller is made the adjustable one laterally; and it consists in pivoting the parallel yoke, to which that roller is attached, by pivoted rods, to the frame at a point intermediately between the front and rear end of the said yoke, and applying the counteracting spring to the cross-bar at the rear end of the yoke.

To enable others to make and use my invention, I will describe its construction and operation.

I use in this machine the same cutting apparatus which was presented in my former application, patented February 17, 1863, the knife or knives being attached to revolving heads *h* in such a manner as to produce an

upward shearing stroke across the face of the throat-bar *b*. The feed-rollers *R* are also arranged, geared, and operated the same as formerly; but the parallel yoke *y*, which supports the under or variable feed-roller, instead of having the rear end pivoted to the frame, as heretofore, and the spring *s* extended to the front bar, *a*, the yoke is pivoted to the frame at an intermediate point between the front and rear, and the end of the spring *s* rests upon the rear bar, *c*, of the yoke.

It will be seen that by this arrangement of the parts the spring has a leverage in its favor in supporting the roller, whereby a much lighter and shorter spring may be used with equally good effect. The spring is secured to the frame by a single screw-bolt, *d*.

What I claim as my invention, and desire to secure by Letters Patent, is—

The relative arrangement of the spring *s* with the yoke *y*, the latter being pivoted to the frame of the machine by the pivots *g*, which are located at a point intermediately between the bar *c* and the pivots *f*, to which the supporting-bars *r* are hinged, for the purpose set forth, the parts acting conjointly, in combination with the upward cut.

ALEX. GORDON.
